UNITED STATES PATENT OFFICE.

SUMTER B. BATTEY, OF NEW YORK, N. Y.

POCKET-LIGHTER.

No. 908,728.

Specification of Letters Patent.

Patented Jan. 5, 1909.

Application filed August 24, 1908. Serial No. 450,064.

To all whom it may concern:

Be it known that I, SUMTER B. BATTEY, a citizen of the United States, and a resident of the borough of Manhattan, city of New York, county and State of New York, have invented certain new and useful Improvements in Pocket-Lighters.

This invention relates to self-igniters and more particularly to self contained portable pocket lighters for lighting cigars and for other purposes.

An object is to increase the reliability of such a device, more especially, to increase the reliability in the self-ignition of a vapor burner provided with a catalytic agent.

To these ends it is an object to provide for the positive delivery, at the will of the operator, of inflammable gaseous medium, which term includes fixed gases and inflammable vapors, to the burner and to the catalytic agent.

A further object is to provide for the permanent separation of the burner and igniting body from the interior of the vessel containing the source of inflammable gaseous medium.

The invention also contemplates the adaptation of a Bunsen burner for use in a pocket lighter; also the combination with a self-igniting burner of a second burner for more continuous use; also the use of a carburetor of positive action for generating the inflammable vapor for the self-igniter.

In addition, it is the object of the invention to improve the general construction of self-igniters and to do away with the necessity of separating respective parts in their operation.

The above and further objects will be apparent from the following description and claims read in connection with the accompanying drawings which form part of this application, in which like characters designate corresponding parts, and in which,—

Figure 1 is a sectional elevation of one form of my device; Fig. 2 is a similar view of a modification; Fig. 3 is a similar view showing modified parts and an additional burner; Fig. 4 is a cross-section on line IV—IV of Fig. 3; Fig. 5 is a side view of a modified outer shell; Fig. 6 is a fragmentary vertical section through the two shells showing the modification of Fig. 5; and Fig. 7 is a detail of the check valve.

In the drawings 1 designates a hollow shell

fitting snugly within and telescoping with the shell 2.

3 is the bottom closure for the shell 1, which may extend out beyond the diameter of the shell to form a finger engageable ring 4.

5 is the top closure for the shell 2. These shells may be of any desired cross-section, although a circular cross-section is illustrated.

In Figs. 1 and 2 an interior packing of absorbent material and designated by 6 is illustrated, and is located within the chamber formed by the shells and closures just described. This packing may be saturated with a liquid capable of producing an inflammable gaseous medium such as hydro-carbon vapor.

Suitably secured to the outer shell 2 is a vapor burner 7, which may be in the form of a Bunsen burner, as illustrated, and may be provided with the deflecting removable hood 8, providing the burner opening 9. It should be understood, however, that the burner may be used without the hood 8 if desired. A body of material capable of catalytic action, that is, a catalytic agent, is designated by 10, in the form of a pellet which may be of platinum sponge or any suitable substance. This pellet may have projecting therefrom one or more brushes 11, formed of attenuated threads of platinum or the like. The pellet is suitably supported by platinum threads 12, secured to the arms of a ring-like yoke 13 frictionally engaging the inner walls of the burner 7 and resting against the rib 14.

A duct 15 leads from the pin hole opening 16 through the wall of the shell 2 to the interior of the Bunsen burner 7 beneath the catalytic agent 10. If desired the duct 15 may be upwardly directed within the Bunsen burner, as indicated, and its exit opening may be covered by a wire gauze 17 to prevent back-firing, it being understood that the wire gauze may be omitted or otherwise located if desired.

In Fig. 1 a nipple 18 is illustrated, providing an opening 19 into the chamber within the shells 1 and 2. Threaded upon the nipple 18 is a manually operable cap 20 with side openings 21, whereby the unscrewing of the cap opens the chamber within the shells to the atmosphere and the screwing down of the cap closes the duct 19. Provisions are also present for closing the pin hole opening 16 of the duct 15. In Fig. 1 the rim 22 of the shell 1 fits snugly over the opening 16 when the shells are completely telescoped as

illustrated. This is likewise the case in Figs. 2 and 3. If desired, the rim of the shell 1 may be split as shown by 23, whereby a permanent outward spring may be im- 5 parted to the rim of the shell 1 to insure a tight closure of the same upon the mouth of the opening 16. Also if desired a longitudinal rib 24 may be struck out of the shell 2 and provided with an off-set portion 25 and 10 a staggered portion 26, forming substantially one part of a bayonet joint, as will hereinafter be apparent. In this modification the pin hole opening 16 pierces the wall of the rib 24, and a closure 27 may be at- 15 tached to the rim 22 so as to travel in the interior of the rib 24. The closure 27 may have inherent resilience or may be resiliently pressed against the inner wall of the rib 24 by the resilience of the rim 22. This closure 27 20 also serves as a traveler or stop for limiting the relative movement in a longitudinal direction of the shells 1 and 2. Obviously the relative longitudinal movements of the shells 1 and 2 are limited in extent to the travel of 25 the closure or stop 27 in the longitudinal rib 24, although a rotary movement of the shell 1 permits the complete removal of the shell 1 when the stop 27 reaches the rib 26, the exit of the bayonet joint.

30 In Fig. 2, a tube 28 opening to the atmosphere at 29 extends longitudinally within the shell 2 and terminates in position to be closed by a plug or washer 30, which may be affixed to the bottom closure 3 of the shell 1. In this 35 modification the packing 6 is provided with a cylindrical opening 31 to permit the passage of the tube 28. If desired, the tube 28, which provides an opening from the chamber within the shells to the atmosphere, may 40 be provided with an automatic check valve 32, this valve being shown in detail in Fig. 7. It may be of any suitable construction. That illustrated comprises a disk-like closure 33 with upwardly projecting and inturned 45 fingers 34 which take over the crimped edge 35 of the mouth of the tube 28. The tube 28 may be fixed in position in any suitable manner. In Fig. 2 it may be soldered or brazed to the inturned nipple 35, or it may be ex- 50 panded and spun over the opening in the closure 5, as shown by 36 in Fig. 3. If desired the packing of absorbent material may be omitted and suitable vaporizable liquid may be contained directly in the vessel 55 formed by the shell 1 and the closure 3. This is indicated by 37 in Figs. 3 and 4. When the check valve 32 is provided, the washer or plug 30 may be used or not at will; it is illustrated in Fig. 3. Also if desired a sec- 60 ond burner 38 may be combined with the mechanism. It is shown in the form of a cylinder 39, threaded into the removable nipple 40 for tank 41 and through which the wick 42 extends into the combustible vapor 65 producing fluid 43. A removable cap 44 is

provided for covering the burner 38 and may be secured thereto by a chain 45. The tank 41 is fixed to the outer shell 2 by soldering or brazing, and has supporting feet 46.

The chamber within the shells 1 and 2 70 serves as a source of supply for an inflammable gaseous medium. This medium may be developed from any suitable hydro-carbon to be contained within the vessel. In telescoping, shells 1 and 2 as previously de- 75 scribed with their closures, form an hermetically sealed chamber for the vapor producing medium. To operate the lighter the shells 1 and 2 are extended one from the other by grasping the rim 4 of shell 1 and 80 pulling them out an extent indicated by the travel of the stop 27 in the rib 24 of Figs. 5 and 6, as previously described, this extent of opening being approximate for all the 85 embodiments, it being understood that the lower wall of offset rib 25 coöperating with stop 27 merely illustrates means for preventing the complete separation of the shells during the operation of the lighter.

Before pulling apart the shells 1 and 2 of 90 the device shown in Fig. 1, the cap 20 should be unscrewed to open the duct 19, whereupon, on the pulling apart of the shells, a jet of air is directed against the vaporizable material within the shells, the parts operat- 95 ing as a carburetor to produce the inflammable vapor. In all the embodiments the initial pulling apart of the shells uncovers the opening 16 of the duct 15, which opening itself may likewise serve as an ingress to air. 100 The entering air immediately effects the vaporization of the liquid within the shells, whereupon the two shells may be pressed telescopically together by thumb and finger pressure upon the closures 3 and 5. In the 105 modification shown in Fig. 1 the cap 20 should first be closed upon the opening 19, in the modification shown in Fig. 2 the finger or thumb serves as a closure for the opening 29, and likewise in the modification shown 110 in Fig. 3. The shells constitute means for compressing the measured charge of inflammable gaseous medium in the chamber they form and this means operates to force out a small jet through the minute orifice or pin-hole opening 16 into the duct 15 which serves as an expansion duct in which the inflammable vapor is rendered uniform in composition and expands so as to reduce its pressure to a desired working pressure for supplying the 115 burner 7. In the type of burner illustrated the vapor is well mixed with air entering the bottom of the burner about the duct 15 and burns with an intense flame. The minuteness of the orifice 16 requires that an appreciable duration of pressure be applied to collapse the shells 1 and 2 and consequently prevents the too sudden delivery of vapor to the burner and its consequent waste.

In the apparatus described, inflammable 130

vapor may be produced positively and at will and it may be delivered positively and at will and in measured quantities to the burner and to the igniter. The igniter is shown as a 5 catalytic agent against which the vapor is first positively delivered in the presence of air. It is instantaneously heated by a process well known for a decade.

Incandescence is imparted to the platinum 10 brushes 11 and the vapor is ignited and continues to burn at the mouth of the burner opening 9 as long as vapor is supplied to it. At all times all the fragile parts are protected and to operate the device no parts are separated one from the other.

In Figs. 2 and 3 the closure 5 is shown conical in form, thus presenting a comparatively restricted surface 47 about the opening 29 which is a provision for closing the opening 20 29 by the operator's finger or thumb. When the tube 28 is provided with a check valve 32 it is not necessary that the operator's finger close the opening 29.

If it is desired that a more continuous 25 flame be provided, the combination shown in Figs. 3 and 4 may be employed. If the cap 44 is removed the exposed end of the wick 42 will be lighted by the flame issuing from the burner opening 9 and the burner 38 may be 30 employed to supply a continuous flame.

The pocket lighter may be readily charged with vaporizable liquid by entirely removing the bottom shell 1 and filling it with suitable liquid, whereupon it is replaced within the 35 shell 2.

Although there have been illustrated and described several embodiments of the invention, it is to be understood that these are for purposes of illustration only, and that the 40 various elements shown in the several figures may be combined in a manner other than that illustrated.

What is claimed and what is desired to be secured by United States Letters Patent is:—

45 1. A pocket lighter comprising a source of supply for an inflammable gaseous medium; a burner for said medium; material capable of catalytic action; and means for positively delivering vapor under pressure from said 50 source to said burner and to said material capable of catalytic action.

2. A self-contained, portable self-igniter 55 as an article of manufacture comprising means providing a chamber for containing a combustible gaseous medium and capable when manipulated of exerting pressure upon the gaseous contents of said chamber; a burner exterior to said chamber and comprising a casing inclosing a catalytic agent; and 60 means providing a duct leading from said chamber to the interior of said casing, whereby said combustible gaseous medium may be positively delivered to said burner and to said catalytic agent.

65 3. A self-contained, portable self-igniter

as an article of manufacture comprising means providing a chamber for containing a vaporizable liquid, said means providing for the intake of air to be carburized by said liquid and for applying pressure to the gaseous medium within said chamber; a burner exterior to said chamber and comprising a casing inclosing a catalytic agent; and means providing a duct leading from said chamber to the interior of said casing, whereby said combustible gaseous medium may be positively delivered to said burner and to said catalytic agent.

4. In a pocket lighter, two telescoping shells closed at their opposite ends and relatively movable; a tube opening to the atmosphere and extending interiorly of one of said shells for admitting air to the interior thereof and automatic means for closing said tube to the atmosphere; an exterior vapor burner; and a duct leading from the interior of said shells to said burner.

5. In a pocket lighter, two telescoping shells closed at their opposite ends and relatively movable; a tube opening to the atmosphere and extending interiorly of one of said shells for admitting air to the interior thereof and automatic means for closing said tube to the atmosphere; an exterior vapor burner; and a duct leading from the interior of said shells to said burner; and provisions for closing said duct.

6. In a pocket lighter, two telescoping shells closed at their opposite ends and relatively movable; a tube opening to the atmosphere and extending interiorly of one of said shells for admitting air to the interior thereof and automatic means for closing said tube to the atmosphere; an exterior vapor burner; a duct leading from the interior of said shells to said burner; and provisions for closing said duct.

7. As a self contained portable device in combination, two telescoping shells closed at their opposite ends and relatively expandible and collapsible; provisions for containing within said shells a liquid for producing a combustible gaseous medium; a controllable air inlet for insuring the passage of air to be carburized over said liquid upon the expanding of said shells; a burner for gaseous medium outside of said shells; a self-igniting device for said burner; and a duct extending from the interior of said shells to said burner and self-igniting device through which duct said gaseous medium may be forced by forcibly collapsing said shells.

8. As a self contained portable device in combination, two telescoping shells closed at their opposite ends and relatively expandible and collapsible; provisions for containing within said shells a liquid for producing a combustible gaseous medium; a finger controllable air inlet for insuring the passage of air to be carburized over said liquid upon the

- expanding of said shells; a burner for gaseous medium outside of said shells; a self-igniting device for said burner; and a duct extending from the interior of said shells to said burner and self igniting device through which duct said gaseous medium may be forced by forcibly collapsing said shells.
9. As a self contained portable device in combination, two telescoping shells closed at their opposite ends and relatively expansible and collapsible; provisions for containing within said shells a liquid for producing a combustible gaseous medium; a controllable air inlet for insuring the passage of air to be carburized over said liquid upon the expanding of said shells; a burner for gaseous medium outside of said shells; a self-igniting device for said burner; and a duct extending from the interior of said shells through a pin hole opening then through an expansion chamber to said burner and self-igniting device through which duct said gaseous medium may be forced by forcibly collapsing said shells.

10. As a self contained portable device in combination, two telescoping shells closed at their opposite ends and relatively expansible and collapsible; provisions for containing within said shells a liquid for producing combustible gaseous medium; a finger controllable air inlet for insuring the passage of air to be carburized over said liquid upon the expanding of said shells; a burner outside of said shells; a self-igniting device for said burner; a duct extending from the interior of said shells to said burner and self-igniting device, through which duct said gaseous medium may be forced by forcibly collapsing said shells; and a second independently and continuously fed burner within the ignition range of said burner and self-igniting device.

In testimony whereof, I have signed my name to this specification, in the presence of two subscribing witnesses.

SUMTER B. BATTEY.
